UNITED STATES PATENT OFFICE.

ISAAC A. SCHWARZ, OF PHILADELPHIA, PENNSYLVANIA, ASSIGNOR TO
LAZARUS SCHWARZ & CO., OF SAME PLACE.

DESIGN FOR HAT OR BONNET TRIMMING.

SPECIFICATION forming part of Design No. 28,407, dated March 22, 1898.

Application filed December 31, 1897. Serial No. 665,240. Term of patent 3½ years.

To all whom it may concern:

Be it known that I, ISAAC A. SCHWARZ, a citizen of the United States, residing in Philadelphia, Pennsylvania, have invented a new and original Design for Hat or Bonnet Trimming, of which the following is a specification.

My design is fully shown in the accompanying drawing, which represents a perspective view of a piece of the trimming.

The design comprises opposite rolls *a a* of stiff network, between which is interposed an upstanding or projecting ruche *b*, this combination constituting the essential feature of the design.

I claim—

The design for hat or bonnet trimming, substantially as described and as shown in the accompanying drawing.

In testimony whereof I have signed my name to this specification in the presence of two subscribing witnesses.

ISAAC A. SCHWARZ.
